UNITED STATES PATENT OFFICE.

FRANCIS M. CASE, OF CLEVELAND, OHIO, ASSIGNOR, BY MESNE ASSIGNMENTS, TO THE HOOVER COMPANY, OF NORTH CANTON, OHIO, A CORPORATION OF OHIO.

BRUSH-ADJUSTING DEVICE FOR SUCTION CLEANERS.

Application filed July 26, 1917. Serial No. 182,870.

To all whom it may concern:

Be it known that I, FRANCIS M. CASE, a citizen of the United States, residing at Cleveland, in the county of Cuyahoga and State of Ohio, have invented a certain new and useful Improvement in Brush-Adjusting Devices for Suction Cleaners, of which the following is a specification.

My invention relates to improvements in brush adjusting devices for suction cleaners. It has for one object to provide means whereby the brush in the suction nozzle of the suction cleaner may be adjusted toward and from the floor. This is particularly important because of the need of setting the brush down from time to time as the bristles wear off. With a rapidly rotating power driven brush the bristles do wear off and it becomes from time to time necessary to bring the brush body nearer to the carpet as otherwise the brush action will be ineffective due to the shortness of the bristles.

My invention, therefore, provides means for easily and conveniently adjusting the brush and means which will make sure that when the operator adjusts the brush it will be so adjusted that the two ends are level, thus guarding against the possibility of having the brush in an incorrect position in the nozzle. Other objects of my invention will appear from time to time in the specification.

Figure 1 is an inverted plan view of the nozzle end of a suction cleaner;

Figure 2 is an end elevation of the brush supporting means showing the casing in section at the line 2—2 of Figure 1;

Figure 3 is an end elevation of the brush adjusting plate;

Figure 4 is a section along the line 4—4 of Figure 1.

Like parts are indicated by like characters in all the figures.

A is a suction cleaner housing shown here only in part. It is provided with an open suction nozzle A¹ in which is rotatably mounted a brush A². The brush is provided with a pulley A³ over which passes a driving belt A⁴ driven from any suitable source of power not here shown.

The brush body is hollow. It has at either end bearing sleeves B which are preferably fixed in the hollow brush body. They are rotatably mounted upon a shaft B¹. This shaft B¹ has its ends squared off and is of such length that the squared off ends fit into

apertures B², B² in bosses B³, B³ on adjusting washers B⁴. These washers B⁴ have annular rings B⁵ projecting inwardly and surrounding the end of the brush though out of contact with it. On their outer sides 60 these washers are provided with bosses B⁶. These bosses are on the same axial line as the center of rotation of the brush. They are each surrounded by an annular channel B⁷. B⁸ is a slot in the boss B⁶ for a screwdriver.

C, C are spiral cam grooves in the outer faces of the adjusting washers. These grooves have at certain points along their lengths depressions C¹. C², C² are supporting plates provided as at C³ with elongated slots of the same width but longer than the diameter of the bosses on the adjusting washers. These plates have projections C⁴ adapted to engage the cam slots and depressions 70 on the faces of the adjusting washers, the arrangement being such that as the washers rotate the center about which the cam groove rotates will move up or down because the projections engaging the cam grooves will as 80 the washer rotates insure this movement. The supporting plates have ears C⁵ which act as stops to prevent the brush device from being too far forced into the hood and to compel it to come always to the same relative position. They serve also as a handle by means of which the brush and its associated parts can be easily removed from the hood. The washer is held in different 85

adjusting positions by the engagement of the 90 projections with the depressions in the bottom of the cam groove and there is sufficient play to permit the projections to leave the depressions in the bottom of the grooves and still not leave the grooves. Since the washers 95 are mounted on the shaft one washer when rotated will cause the rotation of the other and thus both ends of the brush will be equally adjusted. The holding plates are 100

held together by a cross bar C⁶ which rests against the inside front wall of the suction nozzle. It is more or less elastic in its action so that the parts may be sprung into position and the brush supporting device be held normally together as a unit. This unit may 105 be placed in or withdrawn from the open mouth of the brush, being held in position by the spring fingers C⁷ which engage lock pins C⁸ on the inside of the nozzle.

D D are a series of guard or protecting 110

5 fingers mounted in integral clips or lugs D^1 on the cross bar C^5 . These fingers extend in the plane of the open mouth of the nozzle beneath the brush being bent up at their 10 rear ends at D^2 into substantial conformity with the path of the ends of the bristles of the brush whereby the brush as it rotates in the direction indicated by the arrow in Figure 2 will tend to prevent movement of foreign 15 matter along the fingers toward the front even though the movement of the machine itself may be reversed. These guard fingers it will be noted, divide the open mouth into a series of transverse openings joined by a longitudinal opening at the rear.

15 It will be evident that while I have shown in my drawings an operative device, still many changes might be made both in size, shape and arrangement of parts without departing from the spirit of my invention and I wish, therefore, that my drawings be regarded as in a sense diagrammatic.

20 It will also be observed that the brush adjusting cam device is also the thread guard for the end of brush, the two functions being performed by one and the same structure.

25 The use and operation of my invention are as follows:—

30 The apparatus shown in Figure 1 is ready for operation as a suction cleaner. If the operator wishes to adjust the height of the brush in the open mouth of the hood he first releases the belt from its driving pulley and he then releases the spring latch fingers and 35 then taking hold of the ears shown on either side of the open mouth he rotates the whole brush assembly upwardly until the holding spring fingers are disengaged from the open mouth, whereupon he can lift the brush and its associated parts from the mouth. With 40 the brush and supporting parts removed from the nozzle there is spring enough in the metal to permit the adjusting washers to be rotated. This can be done by means of 45 a screw driver preferably inserted in the slot in the end of the boss on the adjusting washer. The two washers turn together and the projections on the supporting plate travel in the grooves and drop into the depressions in the bottom of the grooves on 50 the adjusting washers. The associated cross bar holds the supporting plates in the proper position with relation to each other and 55 yieldingly toward each other so that the brush and its adjusting plates are held yieldingly between the two supporting plates. The rotation of the adjusting plates in the manner suggested obviously causes the brush to move vertically with respect to the supporting plates and if the parts are properly proportioned the two ends of the brush will be held so that the brush will always have the proper parallelism with respect to the parts with which it is associated for the 60 65 projections on the plates will always drop

into corresponding depressions on the adjusting washers.

The arrangement is such that the parts cannot be sprung apart to effect this adjustment when they are within the casing. 70 When, however, the brush and its associated parts are removed from the casing then the parts can be operated to effect the adjustment and the brush will then be returned to the casing its new adjustment being that 75 which the operator requires.

The presence of the frame and guard fingers and associated parts furnishes the operator with a guide to determine how much of an adjustment to make. 80

I claim:—

1. In a suction cleaner a brush, a shaft upon which it is rotatably mounted, an adjusting plate fixed on each end of the shaft, supports for said plates and means responsive to a rotation of said plates for changing the height of the brush said means comprising a cam groove and a member engaging it. 85

2. In a suction cleaner a brush in combination with a support member at one end of the brush and a frame member at the same end of the brush, the support and frame piece held rotatably and slidably together, and positive interlocking devices comprising a projection on one member, a recess on the other member, the projection adapted to be received in the recess to lock the frame and support on said members adapted when the support and frame are moved with reference to each other to cause one of them to slide on the other to adjust the height of the brush. 90

3. In a suction cleaner a brush in combination with a support member at one end of the brush and a frame member at the same end of the brush, the support and frame piece held rotatably and slidably together, and positive interlocking devices on said members adapted when the support and frame are moved with reference to each other to cause one of them to slide on the other to adjust the height of the brush, said interlocking devices comprising a cam on one part and an engaging member on the 100 other. 105

4. In a suction cleaner a brush in combination with a support at one end of the brush and a frame piece at the same end of the brush, the support and frame piece held rotatably and slidably together, and interlocking devices on them adapted when the support and frame are moved with reference to each other to cause one of them to slide on the other to adjust the height of the brush, said interlocking devices held in yielding engagement, and a hood which encloses the parts and holds the interlocking devices rigidly together. 115 120

5. In a suction cleaner a brush in combi- 130

nation with a support at one end of the brush and a frame piece at the same end of the brush, the support and frame piece held rotatably and slidably together, and interlocking devices on them adapted when the support and frame are moved with reference to each other to cause one of them to slide on the other to adjust the height of the brush, said interlocking devices comprising
10 a cam on one part and an engaging member on the other held in yielding engagement, and a hood which encloses the parts and holds the interlocking devices together.

6. In a suction-cleaner a brush, a shaft
15 upon which it is rotatably mounted, an adjusting plate on each end of the shaft, supports for said plates, said supports provided with vertical guides, the shaft ends movable in said vertical guides, said adjusting plates
20 and supports having interlocking members including a cam adapted by the rotation of the adjusting plate to vertically change the height of the brush.

7. A supporting device comprising a housing and supporting plate members detachably fixed thereto, and a brush holding member rotatably mounted with respect to such plate member, one of said members being resilient, one of said members being provided with a projection and the other 25 with a cam groove receiving such projection.

8. A supporting device comprising a housing and supporting plate member, a brush holding member, one of said members being resilient and provided with a projecting lug, 35 and the other of said members being provided with a cam groove and spaced depressions, such cam groove and lug reacting upon relative rotation of the members to move one of said members bodily with respect to the other, and said lug and depressions reacting to lock the members in different predetermined positions.

In testimony whereof I affix my signature
this 18th day of July, 1917.

FRANCIS M. CASE.
